SIGNALING DEVICE.
APPLICATION FILED DEC. 14, 1911.

Patented July 23, 1912.

2 SHEETS—SHEET 2.

UNITED STATES PATENT OFFICE.

GUSTAVE FORTMANN, OF PHILADELPHIA, PENNSYLVANIA, ASSIGNOR OF ONE-HALF
TO GEORGE W. COOK, OF PHILADELPHIA, PENNSYLVANIA.

SIGNALING DEVICE.

1,033,572.

Specification of Letters Patent. Patented July 23, 1912.

Application filed December 14, 1911. Serial No. 665,633.

To all whom it may concern:

Be it known that I, GUSTAVE FORTMANN, a citizen of the United States, residing at Philadelphia, in the county of Philadelphia and State of Pennsylvania, have invented 5 certain new and useful Improvements in Signaling Devices, of which the following is a specification.

My invention relates to improvements in 10 signaling devices, and more particularly to an attachment for automobiles which is adapted to be attached to the rear of the automobile, and contain a plurality of signals under the control of the chauffeur, who may 15 electrically control the operation of any of the signals so as to indicate to those in the rear of the machine just what the chauffeur is about to do with his car.

A further object is to provide improvements of this character which consists of a 20 plurality of transparencies covering separate chambers illuminated by electric lights, which lights are under the control of the chauffeur by reason of push buttons or 25 switches located adjacent the chauffeur's seat, preferably though not essentially, upon the steering post or adjacent the steering wheel, and combine with such signaling device a license tag holder and a danger signal, the light illuminating said danger signal and license tag being lighted at all times 30 after dark, the other lights being turned on and off by the chauffeur as he guides the car.

With these and other objects in view, the 35 invention consists in certain novel features of construction and combinations and arrangements of parts as will be more fully hereinafter described and pointed out in the claims.

40 In the accompanying drawings: Figure 1, is a view in side elevation illustrating an automobile in dotted lines, and showing my improvements in connection therewith.

Fig. 2, is a diagram of the electric circuits 45 controlling the several lights. Fig. 3, is a view in cross section on the line 3—3 of Fig. 4. Fig. 4, is a view in front elevation of my improved signal box, and Fig. 5, is a view in vertical section on the line 5—5 of 50 Fig. 4.

1, represents my improved signal box which may be made of metal or other suitable material, and is preferably rectangular in form divided by a series of horizontal

partitions 2 into a plurality of chambers 3. 55 On the outer ends of these partitions 2, channel guides 4 are secured, and channel guides 5 are secured by brackets 6 to the upper and lower ends respectively of said box, and these channel guides are adapted 60 to receive transparencies 7. These transparencies are preferably of glass containing signals which are transparent, and readily observed by reason of the fact that the rest of the glass is rendered practically opaque. 65 These transparencies are secured in their guides by means of a frame 8 which is connected at one edge by hinges 9 with the box 1, and at its other edge is adapted to be secured in closed position by a hasp 10 and 70 padlock 11.

The frame 8 is of such a dimension and thickness that it is positioned against the ends of all of the transparencies when said frame is in closed position, so that none of 75 the transparencies can move except the frame be open, and to prevent rattling of the slides, suitable cushioning strips 12 are positioned in the channel guides 4.

Electric lamps 13 are located in the several chambers 3, are secured to the back of the box 1, and are connected in an electric circuit as will be hereinafter explained. The lamp 13 in the lower chamber 3 is provided with a reflector 14 in the upper portion of the chamber so as to throw the light not only through the transparency, but also 80 downwardly through an elongated opening 14^a onto a license tag 15. This license tag 15 may be of any ordinary character, and is 85 supported in a holder 16 secured by brackets 17 to the bottom of the box 1 at the rear of said box. This holder 16 has channel guides at its top and bottom, and one end to receive and hold the license tag 15 and a 90 thumb screw 18 is screwed into the holder at one end to prevent the license tag from moving out of the holder when once inserted therein, yet allow tags to be changed as 95 desired.

The box 1 is secured by brackets 19 or otherwise to the rear of an automobile illustrated in dotted lines in Fig. 1. While the lights may be controlled from various parts of the automobile, I have illustrated a preferred form in which a series of push buttons or switches 21 are supported on the steering post 20 of the automobile. These 100 105

push buttons or switches are connected in circuit with the several lights, and with a battery 22 as seen most clearly in Fig. 2, so that the chauffeur may cause any of the electric lamps to become illuminated as he desires.

While, of course, the particular wording of the transparencies may be changed to suit the trade, those illustrated are most needed and are as follows: "Stop—R" indicates that the machine is going to move to the right and stop. "Stop—L" indicates that the machine is going to the left and stop. "Turn—R" indicates that the machine is going to turn to the right, and "Turn—L" indicates that the machine is going to turn to the left. The bottom transparency containing the word "Danger" is of course to be the ordinary danger signal required at the rear of every car, and the lamp for such signal will be lighted at all times after dark, and this lamp will serve the double purpose of illuminating the license tag 15 below, so that when my improved signaling device is attached to an automobile, no lamp such as ordinarily used is required for the back of the car. If one of the transparencies becomes broken, or for any reason it is desired to change them it is simply necessary to swing the frame 8 to open position, and withdraw any of the transparencies and insert others.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what

I claim as new and desire to secure by Letters Patent is:

1. An automobile signaling device, comprising a box adapted to be secured to the rear of an automobile, a series of horizontal partitions in said box dividing the same into a plurality of chambers, channel guides secured to said partitions and to the upper and lower ends of said box, transparencies of approximately the same length as the width of the box mounted to slide in said channels, and a rectangular frame hinged at one side edge to said box and at its other side adapted to be removably locked to said box, said frame fitting against the side and end walls of the box and confining the ends of all of said transparencies and securing them in the channels, substantially as described. 60

2. An automobile signaling device, comprising a box adapted to be secured to the rear of an automobile, a series of horizontal partitions in said box dividing the same into a plurality of chambers, lights in said chambers, guides secured to said partitions and to the upper and lower ends of the box, transparencies of approximately the same length as the width of the box mounted to slide in the guides and shorter than the box, 70 and a rectangular frame hinged at one side edge to the box and fitting against the side and end walls of the box and adapted to confine the ends of said transparencies, substantially as described. 75

In testimony whereof I have signed my name to this specification in the presence of two subscribing witnesses.

GUSTAVE FORTMANN.
